UNITED STATES PATENT OFFICE.

EARL R. HAMILTON, OF NITRO, WEST VIRGINIA.

DISTILLATION APPARATUS.

Application filed November 1, 1923. Serial No. 672,099.

This invention relates to improvements in distillation apparatus and the object thereof is to provide an apparatus which may be operated continuously, although capable of being operated intermittently, to produce a more effective and complete distillation of the material with which the apparatus is charged.

A further object of the invention is to provide for the fractional collection and delivery of the pure distillate and also to save the more impure distillate.

A further object of the invention is to provide a continuous distillation apparatus in which the circulation of the charge is maintained by the action of gravity.

Another object of the invention is to provide a distillation apparatus having separate chambers for the material, each of which may be maintained at a different temperature, while the apparatus is heated from a single source of heat.

A further object of the invention is to provide a distillation apparatus in which the more violent reaction of the fresh charge will take place in the presence of a lower temperature than that finally employed.

A further object of the invention is to provide a continuously operated distillation apparatus which will not be subject to so great pressures from the volatile products of reaction as in usual intermittently operated retorts.

More particularly the invention relates to improvements in apparatus for manufacturing nitric acid from a suitable nitrate and sulphuric acid. In the usual process of making nitric acid the nitrate and sulphuric acid are placed in a cool or slightly warm retort which is then highly heated causing the chemicals to react and give off nitric acid which is collected and delivered to a suitable condensing apparatus. After the nitric acid has been formed and expelled from the retort, the spent sulphuric acid and the sulphates which are formed during the process are run off and the retort allowed to stand until cool, after which the retort is again charged with nitrate and sulphuric acid and the process repeated. Thus the process is an intermittent one.

The present invention comprises a retort, which is particularly designed for continuous operation, but which is capable of intermittent use, having a plurality of communicating chambers, preferably concentrically

arranged, and through which the material is progressively passed by the action of gravity and the material progressively heated during its passage through the chambers. 60

Means are preferably provided for collecting and discharging the distillate which is produced from the material in one or more of the chambers, which is subjected to a lesser degree of heat, separately from that which is in a more highly heated chamber or chambers.

In the particular embodiment of the invention disclosed herein the retort comprises an inner container having a plurality of concentric communicating chambers located within an outer container which entirely surrounds the inner container and forms a jacket therefor. The charge is introduced into the innermost chamber and then passes in turn through each next outer chamber until it reaches the outermost chamber and is discharged therefrom in the continuous operation of the device through an outlet pipe which communicates with the outer container at a predetermined distance above its bottom, thereby maintaining a sufficient amount of the fluid charge in the space between the inner and outer containers to form a liquid jacket for the inner container and its chamber.

The retort is further provided with a hood for the outer chamber and with one or more hoods for collecting the distillate formed in the inner chamber so that the distillates formed in selected inner chambers may be kept separate from the more impure distillate which is expelled from the partially spent charge.

By reason of this construction a distillation apparatus is provided in which the chemical reactions may be produced with a minimum amount of fuel consumption, thus avoiding much loss of fuel necessitated in intermittently operated systems from the required cooling down of the retort to permit the removal of the residuum after the distillation of the charge is completed.

Another object of the invention is to provide a retort which will have a relatively long life. A retort which is intermittently operated is subject to wide variations in temperature due to the cooling down and reheating thereof which causes such contractions and expansions that the retort is likely to crack or to break away from its support. Furthermore, if the retort is not

cooled sufficiently before recharging, a cool charge coming into contact with the bottom of the retort quite frequently causes the retort to crack.

5 In the present invention the retort may be subjected to an even and constant heat throughout the entire time that it is in use, thereby avoiding strains due to expansion and contraction. Furthermore, in the present invention the cool charge is delivered into the inner container which is less highly heated than the outer container and, therefore, less subject to serious strains of expansion and contraction.

10 15 The usual intermittently operated retort comprises merely a single vessel for holding the charge and in which the charge lies against the inner face of the wall, the outer face of which is subjected to the flames of heat. The inner face of the wall of the retort is thus exposed to the strong corrosive action of the raw nitrates and strong sulphuric acid which, in their heated condition, are very reactive. In the retort embodying 20 25 the present invention the bottom of the retort is never exposed to the strongly corrosive action of the fresh charge as the greater part of the reaction takes place within the innermost compartment, the walls of which are not highly heated and which are more or less protected by the partially spent portion of the charge.

30 35 Usual intermittently operated retorts are of a large capacity, capable of containing from five hundred to twelve hundred pounds, more or less, of nitrate with the necessary amount of sulphuric acid. Unless this amount of charge is heated very carefully the first reaction between the chemicals is violent and the products of reaction given off are of such large volume that all parts of the retort are subjected to heavy pressure, sufficient in some instances to blow off the top of the retort, or to force the 40 45 distillate through any slight openings which may exist in the joint between the cover and wall of the retort. In the former case the apparatus would be destroyed, while in the latter case an appreciable amount of distillate is lost and the operators greatly inconvenienced by such escape of the obnoxious distillate.

50 55 By reason of the present invention a charge may be introduced practically continuously in small quantities and violent reaction at any time avoided. Furthermore, the continuously operated retort may be made of lighter construction with no danger that the retort will break by excessive pressure, or that any appreciable amount of distillate will escape.

60 65 The present invention permits the use of smaller condensing apparatus since in intermittently operated retorts the condensing system must be of sufficient capacity to care

for the excessive amount of distillate which is formed during the stage of most violent reaction in the retort, while in the present invention the amount of distillate which is generated in the retort is substantially constant and the condensing system need, therefore, be no larger than is necessary to take care of the usual amount of distillate. Furthermore, where the distillate is delivered to the condenser at a substantially constant rate, a constant flow of cooling fluid may be provided and the danger of sudden overheating or excessive cooling of the parts of the condenser and consequent breakage avoided.

70 75 One of the specific objects of the invention is to provide a distillation apparatus for producing nitric acid and other volatile products in which the charge may be conserved and utilized to its limit. If nitric acid is made in an intermittently operated retort the acid is likely to be decomposed by long contact with the hot walls of the retort during the final stage of the process when the retort is highly heated to drive off the last remnants of the nitric acid. In a continuously operated retort of the character disclosed herein the distillate is formed at approximately the same rate. The tendency of the chemicals to boil over during the frothing stage, at which time the reaction is very violent, and the consequent discharge of an impure product, is avoided.

80 85 90 95 The pure nitric acid is collected and discharged separately from the more or less impure product produced by the final heating of the residuum, and the use of a relatively small condensing apparatus is required.

100 105 Other objects and features of the invention will more fully appear from the following description and the accompanying drawing and will be particularly pointed out in the claims.

110 In the drawing:

Fig. 1 is a vertical sectional view through a preferred form of furnace and retort of a distillation apparatus embodying the invention;

Fig. 2 is a vertical sectional view through a series of retorts which may be successively employed.

115 120 Only such parts of the complete distillation apparatus are illustrated as are necessary to show its construction and means of operation, it being understood that the retort may be used in conjunction with any type of condenser or other apparatus usually employed.

125 The distillation apparatus illustrated herein is designed particularly for the continuous distillation of material, but it is so constructed that it may be also used intermittently.

130 The preferred embodiment of the inven-

tion shown comprises a furnace 1, which may be of any usual character, provided with a fire box 2 and having mounted therein a retort which comprises an outer container 5 having a shell 3 provided with suitable outwardly projecting lugs 4 which rest upon a ledge in the furnace wall. The preferred form of retort is of bowl shape and comprises a hemi-spherical bottom portion 5 which is provided at its lower end with a tangentially extending outlet conduit 6 which communicates with a Y-shaped conduit 7 the lower branch of which is connected to a discharge pipe 8 having a suitable valve 9 by which the outlet may be opened or closed at will. By reason of this construction the entire residuum of the charge may be drawn off when the device is used intermittently as will hereinafter be more fully described. The other branch 10 of the Y-shaped conduit extends upwardly and is connected by one or more intermediate conduits 11 to an upper Y-shaped conduit 12 having a vertical passage 13 provided with an open 25 end and a lateral branch 14 extending through the wall of the furnace and provided with a suitable flange by means of which it may be attached to a suitable pipe to discharge the residuum into a receptacle or other container when the apparatus is operated continuously.

The upper portion of the shell 3 is provided with an annular flange 15 to which is secured a preferably arch-shaped cover or 35 top 16 having an upwardly extending pipe 17 which projects through the top 18 of the furnace and is provided with an annular offset flange 19 to receive the end of a discharge pipe 20 for the distillates and also 40 provides a receptacle 21 for a suitable packing to hermetically seal the joint between the pipe 20 and the pipe 17. The cover 16 is also provided with an upwardly extending pipe 22 having an offset annular flange 23 which provides a packing space 24 for the 45 inlet pipe 25 which extends upwardly from a hood 26 for collecting the purer distillate as will hereinafter be more fully described. The cover 16 is likewise provided with another upwardly extending pipe 27 having an offset flange 28 to provide a packing recess 29 surrounding a pipe 30 which extends upwardly from the hood 26 and provides for the discharge of the purer distillate.

55 In the preferred apparatus as illustrated in the accompanying drawings the furnace wholly encloses the retort so that the dome-shaped cover 16 is protected from the cooling action of the atmosphere and is in fact maintained in a sufficiently heated condition to prevent condensation of water and acid vapors on the inside of the cover which would attack the iron of the cover and also drop back into the receptacle and thereby decrease the efficiency of the apparatus.

The retort also comprises an inner container having a preferably bowl-shaped shell 31, the outer surface of which is provided with downwardly extending legs 32 which rest upon suitable shoulders 33 projecting 70 from the inner face of the outer shell 3. The horizontal upper edge 34 of the shell 31 is well below the top of the upper edge 35 of the outer container 3 and is also located above the level of the outlet pipe 14 so that when the inner container is provided with a continuous, or substantially continuous, supply of material which will overflow over the edge 34 of the inner container into the outer container the spent residuum is finally caused 80 to be discharged by the action of gravity through the outlet 14.

The inner container desirably is provided with one or more vertical concentric partitions which divide the inner container into a 85 series of chambers through which the charge is progressively forced and progressively heated during its passage to the outer container.

In the preferred embodiment of the invention disclosed the shell 31 of the inner container is provided near its bottom with an annular rib presenting a shoulder 36 upon which a cylindrical partition 37 is mounted providing an innermost charging and mixing chamber 38. A plurality of apertures 39 are provided in the lower part of the partition, preferably at the junction of the partition, with the shoulder 36 of said annular rib, so that material charged into the innermost chamber will be caused to pass through the apertures 39 into the next outer chamber. The wall 37 of the innermost chamber extends well above the level of the edge 34 of the inner container so that the innermost chamber may be supplied with sufficient material to cause the material to overflow the wall 34 into the outermost chamber.

The shell 31 of the inner container is also provided with a second annular rib presenting a horizontal shoulder 40 upon which the vertical cylindrical wall 41 of the hood 26 is seated, thus forming another partition providing a chamber 42 which is concentric with respect to the chamber 38. The cylindrical wall 41 of the hood is also provided near its lower end, preferably adjacent the shoulder 40 of the annular rib, with a plurality of apertures 43 through which the charge flows into the chamber 44 between the hood and the shell of the inner container.

In the continuous operation of the apparatus material is charged into the innermost container until its level is above the level of the edge 34 of the inner container whereupon the liquid will flow through the aperture 39 into the next outer chamber 42, thence through the apertures 43 into the chamber 44 and will thence overflow the edge 34 of the inner container into the outer

container until it fills the space between the inner and outer containers to the level of the discharge outlet 14, whereupon the excess of material will be discharged through said outlet. During this operation of the apparatus the heat of the furnace which is applied to the bottom 5 of the shell of the outer container will heat the material between the walls of the inner and outer containers and the material thus heated will transmit more or less of its heat through the wall 31 of the inner container to the material within the concentric chambers of the inner container. As the material of the charge is caused to pass progressively through the apertures 39 and 43, which are located adjacent to the shell of the inner container, it will be progressively heated in the successive chambers and after overflowing the edge 34 of the inner container will be much more highly heated in the outer container. Thus the charge is subjected first to a relatively low degree of heat and thereafter to progressively increasing degrees of heat in the successive chambers until it is finally subjected to the highest heat in the outermost chamber and the distillate completely driven off therein.

By reason of the construction described the purer distillate which is produced in the chambers 38 and 42 by the initial reaction of the chemicals when subjected to a relatively low degree of heat is collected by the hood 26 and delivered through the outlet 30, while the distillate which is produced in the presence of high temperature, and which is more or less impure, is separately collected in the chamber formed by the shell and cover of the outer container and is delivered through the conduit 20. The distillates discharged through the pipes 30 and 20 may be carried through separate condensers, or through separate pipes in the same condenser, or through other devices usually employed in distillation apparatus as will be readily understood. Thus a fractional distillation apparatus is provided in which the purer distillates may be collected separately from the more impure distillates which are produced during the final stage of the process in which the charge is highly heated to drive off the last remnants of the distillate in which case the distillate is sometimes more or less decomposed by reason of the high heat imparted to it from the shell of the outer container.

In order to more thoroughly intermingle the ingredients of the charge a suitable agitator may be provided for mixing the material in the innermost or charging chamber. This chamber is therefore in effect a mixing chamber as well as a charging chamber. The agitator is conventionally illustrated herein as a rotary stirrer comprising a number of blades 45 which are carried at the

lower end of a vertical shaft 46 which extends axially upwardly through the charging conduit 25 of the hood 26 and is journaled in a suitable bearing 47 in the closed upper end of said conduit. The charge may be introduced into the charging conduit in any suitable manner as through a passage 48 provided with a removable, or preferably hinged, cover 49 having locking means 50 for retaining the cover firmly in place between the charging operations, or suitable means may be provided for delivering the charge continuously into the innermost or charging chamber.

In usual types of distillation apparatus, such, for example, as those for producing nitric acid the mixtures of chemicals, such as sodium nitrate and sulphuric acid are introduced in the first instance into a cool retort and subsequently into retorts which are more or less heated. The fresh charge thus introduced produces a violent reaction which produces the gaseous product, such as, nitric acid, so rapidly that an excessive pressure is produced in the retort during the so-called blowing stage which is likely to disrupt the apparatus, or to force the material through the joints between the shell of the retort and its cover. This rapid production of the gaseous product, such as, nitric acid, requires the use of large condensers and other apparatus for handling the product. Furthermore, if the cold charge is introduced into a hot retort the alternate contraction and expansion is likely to crack the retort. By the present invention these undesirable conditions are eliminated.

Where the retort is operated continuously the progressive introduction of charge in small quantities prevents the production of a violent reaction and produces a substantially uniform discharge of the gaseous product both in the preliminary stage and also in the final stage of distillation, thus enabling much smaller condensing apparatus to be used. The residuum is gradually discharged through the outlet in proportion to the introduction of the fresh material. The heating of the retort is maintained constant and the loss of fuel, caused by cutting off or drawing the fire to permit cooling of the apparatus and the necessary reheating, is avoided.

If the apparatus is operated intermittently the spent residuum may be tapped off through the lower outlet 8. When a fresh charge is introduced it will displace the charge in the inner receptacle into the outer receptacle which thereupon forms a jacket for the outer receptacle. The charge thus being introduced is first plunged into the heated material, within the innermost chamber and does not come directly into contact with the shell of the inner receptacle. It, therefore, not only is not subjected to a high

preliminary heat, but is gradually heated so that a less violent reaction takes place than in usual distillation apparatus. Furthermore, in both the continuous and intermittent operations of the apparatus the shell of the inner receptacle is protected against the direct heat of the furnace by the enclosing jacket formed by the shell of the outer receptacle. Thus corrosive action, which results from the contact of a highly heated shell with the freshly formed acid, is avoided.

In the present apparatus the heating of the material in the successive chambers is facilitated by reason of the fact that the liquid in passing from one chamber to the next is caused to flow along and in intimate contact with the shell of the inner container. The cylindrical portion 41 of the hood 26 may be so constructed and proportioned as to collect and deliver the pure product of distillation, while the more impure acid or other distillate, which may be decomposed by long contact with the hot walls of the retort, is separately collected and delivered.

Various other advantageous features of the present invention will be obvious to those skilled in the art.

In Fig. 2 an embodiment of the present invention is illustrated as comprising a series of retorts of the character above described which are not provided with hoods for delivering the gas from a plurality of chambers, but in which the charge is introduced into an inner or charging chamber within the inner container and caused to flow upwardly along the walls thereof and to be discharged into the outer container so that the freshly introduced charge is prevented from contact with the wall of the container to which the direct heat is applied.

The construction disclosed herein comprises a preliminary distillation apparatus having an outer shell 51 with a suitable cover 52 having a charging opening 53 and an outlet 54 for the distillate and an inner container 55 preferably concentric with and spaced apart from the shell of the container. An annular partition 56 within the inner container provides a charging chamber and suitable apertures 57 in the bottom portion of the partition serve to conduct the liquid of the charge along the wall of the inner container. The partition 56 is of greater height than the wall of the inner container so that the charge will gradually overflow the edge thereof into the outer container. A conduit leading from the bottom of the outer container and extending substantially to the level of the top of the inner container leads to a second retort 58 of similar construction having an outlet 59 for the distillate and an outlet 60 for the residuum.

In the operation of this type of apparatus the pure distillate is discharged from the

first retort, while the distillate from the partially spent charge is collected and delivered from the second retort. Obviously any number of retorts of this character may be employed within the spirit and scope of the claims which are intended broadly to cover a distillation apparatus having a series of chambers through which the charge is progressively passed with means for progressively heating the material during its passage and means for delivering the distillate either from the retort as a whole or fractionally from selected chambers. The invention further embraces broadly any type of apparatus comprising an inner and an outer container in which a charge delivered into the inner container is caused to flow into the outer container and to produce a liquid jacket for the inner container which will prevent direct application of the heat to the wall of the inner container for the purposes hereinbefore described.

Having thus described the invention, what is claimed as new, and desired to be secured by Letters Patent, is:

1. A distillation apparatus comprising a retort having a series of chambers, means permitting the charge of material to pass progressively through said chambers, means for progressively heating the material during its passage, means for delivering the distillate and means selectively operable to deliver the residuum either continuously or intermittently, said means comprising a branched outlet from the outermost chamber one branch of said outlet being on a level with the bottom of said chamber and having a valve and the other branch of the outlet extending upwardly and opening at a predetermined distance above the bottom of said chamber.

2. A distillation apparatus comprising a retort having a plurality of concentric communicating chambers, the innermost of which is a charging and mixing chamber, an inlet into the innermost chamber, means for agitating and mixing the charge introduced into said innermost chamber, an outlet from the outermost chamber, means for heating the material in the outermost chamber whereby the material is subjected to different degrees of heat as it moves from the innermost to the outermost chamber and means for delivering the distillate produced in selected chambers.

3. A distillation apparatus comprising a furnace wholly enclosing a retort having a plurality of concentric chambers, an inlet into the innermost chamber and an outlet from the outermost chamber positioned to retain a predetermined amount of material, means for causing the pressure of the material in each chamber to exceed that in the next outer chamber whereby the material will be caused to flow from the innermost

chamber upwardly through the surrounding chambers and its temperature progressively increased, means for delivering the distillate produced by chemical reaction in the inner chambers and separate means for delivering the distillate produced in the outermost chamber in which the material is subjected to the heat of the furnace.

4. A distillation apparatus comprising a retort having a plurality of concentric communicating chambers, an inlet into the innermost chamber and an outlet from the outermost chamber positioned to retain a predetermined amount of material therein, the wall of each inner chamber being higher than the wall of the next outer chamber, whereby each inner chamber may be filled to a higher level than the next outer chamber and caused to overflow by gravity into the next outer chamber, means for heating the wall of the outermost chamber, a hood having a peripheral wall extending into the material in an inner chamber for collecting and delivering the distillate produced by chemical reaction in said inner chamber and means for delivering the distillate produced in the outermost chamber.

5. A distillation apparatus comprising a retort having an outer container and an inner container, annular ribs forming horizontal shoulders, a series of partitions dividing said inner container into a series of concentric chambers, means for charging material into the innermost chamber, said partitions having recesses adjacent the walls of said inner container acting to permit the material to flow progressively outwardly from each inner chamber along and in close proximity to the wall of said inner container and means for supplying heat to the wall of the outer container.

6. A distillation apparatus comprising a furnace, a retort wholly enclosed within said furnace having an inner bowl-shaped container, a series of partitions dividing said container into a series of concentric chambers, the outer of said partitions having a dome to collect and deliver the distillate produced in the chamber enclosed thereby, means for charging material into the innermost chamber, means for causing the material to flow progressively outwardly from each inner chamber along and in close proximity to the curved wall of said inner container and an outer bowl-shaped container substantially concentric with said inner container wholly enclosing the same and arranged to receive material discharged from the inner container and to form a jacket for said inner container and means for delivering the distillate produced in said outer container.

7. A distillation apparatus comprising a retort having an externally heated bowl-shaped outer container, a bowl-shaped inner

container having a wall lower than that of the outer container located concentrically within said outer container and spaced therefrom, an annular partition located centrally within said inner container and forming a charge-receiving chamber, said annular partition having apertures adjacent to its junction with the wall of said inner container to permit material to flow from the charge-receiving chamber upwardly along the wall of the inner container and to overflow into the outer container, a hood having an annular wall depending into the space between said annular partition and the wall of said inner container and provided with means for directing the material along the wall of the inner container and separate means for delivering the distillate collected by said hood from that produced in the outer container.

8. A distillation apparatus comprising a retort having an externally heated bowl-shaped outer container, a bowl-shaped inner container having a wall lower than that of the outer container located concentrically within said outer container and spaced therefrom, an annular partition located centrally within said inner container and forming a charge-receiving chamber, said annular partition having apertures adjacent to its junction with the wall of said inner container to permit material to flow from the charge-receiving chamber upwardly along the wall of the inner container and to overflow into the outer container, a hood having an annular wall depending into the space between said annular partition and the wall of said inner container and provided with means for directing the material along the wall of the inner container, separate means for delivering the distillate collected by said hood from that produced in the outer container and an inlet leading through said hood to the charge-receiving chamber.

9. An apparatus of the class described comprising a container divided into a plurality of concentric communicating chambers, an inlet into the innermost chamber and a branched outlet from the outermost chamber, whereby the charge is made to move through the container from the center outward, one branch of said outlet being on a level with the bottom of the outermost chamber and the other branch of said outlet opening at a predetermined distance above the bottom of said chamber, and a valve in said first mentioned branch adapted to be opened or closed to permit the apparatus to be operated either continuously or intermittently.

10. An apparatus of the class described comprising an outer container, an inner container disposed within the outer container and spaced therefrom, an inlet into the inner container and a branched outlet from the outer container, and a valve disposed in one branch of said outlet whereby the space be-

tween the inner container and the outer container may be emptied without the removal of the contents of the inner container.

11. An apparatus for treatment of nitrates and sulphuric acid comprising, an outer container, an inner container disposed within the outer container and spaced therefrom, said containers having their upper ends disposed in non-communicative relation with each other, an inlet into the inner container

for said nitrates and sulphuric acid, an outlet from the space between the inner container and the outer container for the residuum, and individual vapor outlets from the upper portions of the two containers, the vapor outlet of the inner container being extended through the outer container. 15

In testimony whereof, I have signed my name to this specification.

EARL R. HAMILTON.
